CLAIM

The ornamental design for a gearshift knob cover, as shown and described.

DESCRIPTION

FIG. 1 is a front-right perspective view of a gearshift knob cover showing my new design;

FIG. 2 is a rear-left perspective view thereof;

FIG. 3 is a front elevational view thereof;

FIG. 4 is a rear elevational view thereof;

FIG. 5 is a right side elevational view thereof, the left side being a mirror image;

FIG. 6 is a top plan view thereof; and,

FIG. 7 is a bottom plan view thereof.

The broken lines shown in FIG. 1 are for illustrative purposes only and form no part of the claimed design.
